REFRIGERATOR

Walter Munch, Minneapolis, Minn.

Application March 6, 1933, Serial No. 659,794

3 Claims. (CL. 62—89)

This invention relates to a refrigerator of the type wherein carbon dioxide given off by food stored in a refrigerating compartment is eliminated from said compartment and is replaced by 5 fresh air.

The object of the invention is to provide a refrigerator including a novel and improved arrangement both for eliminating freed carbon dioxide from stored food and for replacing said 10 carbon dioxide by fresh, moist, cool air, and which arrangement will render the present refrigerator more efficient in the performance of its intended services than are more or less similar refrigerators heretofore known.

With the above objects in view, as well as others which will appear as the specification proceeds, the invention comprises the construction, arrangement and combination of parts as now to be fully described and as hereinafter to be 20 specifically claimed, it being understood that the disclosure herein is merely illustrative and intended in no way in a limiting sense, changes in details of construction and arrangement of parts being permissible so long as within the spirit of 25 the invention and the scope of the claims which follow.

In the accompanying drawing forming a part of this specification,

Fig. 1 is a vertical sectional view of a refrigerator in which the features of the invention are 30 incorporated, taken as on line 1—1 in Fig. 2;

Fig. 2 is a vertical sectional view, taken as on line 2—2 in Fig. 1;

Fig. 3 is a vertical sectional view, taken as on 35 line 3—3 in Fig. 1;

Fig. 4 is a vertical sectional view of a modified form of refrigerator made according to the invention, taken as on line 4—4 in Fig. 5;

Fig. 5 is a vertical, longitudinal sectional view, 40 taken as on line 5—5 in Fig. 4;

Fig. 6 is an elevational view of the refrigerator of Figs. 4 and 5;

Fig. 7 is an enlarged detail sectional view corresponding with the disclosure of Fig. 4;

Fig. 8 is an enlarged detail view corresponding 45 with the disclosure of Fig. 5;

Fig. 9 is a vertical sectional view of a further modified form of refrigerator made according to the invention, taken as on line 9—9 in Fig. 10;

Fig. 10 is a vertical, longitudinal sectional view, 50 taken as on line 10—10 in Fig. 9; and

Fig. 11 is an elevational view of the refrigerator of Figs. 9 and 10.

With respect to Figs. 1 to 3 of the drawing and 55 the numerals of reference thereon, 10 represents

a refrigerating case which is as disclosed of rectilinear conformation. Said case 10 suitably supports, in any convenient manner, baffles 11 and 12, said baffles being disposed in the upper portion of the case in spaced relation to each other. 5 The baffles 11 and 12 desirably extend the full width of the case, and slant downwardly and inwardly of the case, the inner edges 13 and 14 of said baffles 11 and 12, respectively, terminating in the same horizontal plane, in spaced relation 10 to each other, as best shown in Fig. 1.

A suitable refrigerating medium, designated 15 and 16, respectively, is situated directly above each baffle 11 and 12, and the inner portions 17 and 18 of said refrigerating mediums terminate in spaced relation to each other, above the baffles and in vertical planes desirably just outside of the vertical planes in which the inner edges 13 and 14 of the baffles lie. The outer edges of the baffles terminate in spaced relation to the adjacent walls 20 of the refrigerating case, and the outer portions 19 and 20 of the refrigerating mediums 15 and 16 terminate above the baffles in vertical planes desirably just inside of the vertical planes of the outer edges of said baffles 11 and 12. The lower 25 portions of the refrigerating mediums are in slightly spaced relation to the baffles 11 and 12, respectively. As shown, the lower portions of the refrigerating mediums are horizontally disposed, providing a space 21 between each refrigerating 30 medium and the baffle therebelow, which space 21 in each instance is of widening extent toward the center of the case 10.

The portion 22 of the case 10, below the baffles 11 and 12, is for the storage of foods, and the 35 spaces 21 communicate with said portion 22 by way of the gap or passage 23 between the inner edges 13 and 14 of said baffles.

The refrigerator includes a novel and improved arrangement for eliminating carbon dioxide freed 40 from food stored in the space 22, and for replacing the removed carbon dioxide by fresh, moist or humid, cool air. As disclosed, the upper wall 24 of the refrigerator case is fitted with spaced apart pipes 25 leading from the upper portion of the 45 refrigerating space to the atmosphere. Each pipe 25 includes perforated branches 26, which perforated branches may extend along an upper corner of the refrigerating space. See Fig. 3. Also, the upper wall of the refrigerator case is fitted with a pipe 27 leading from the atmosphere to the refrigerating space of the case 10. Said pipe 50 27 merges into a pair of spaced apart bifurcated portions, designated 28 and 29, respectively, the former lying adjacent to or contiguous with the 55

inner portion 17 of the refrigerating medium 15, and the latter lying adjacent to or contiguous with the inner portion 18 of the refrigerating medium 16. The bifurcated portions 28 and 29 5 include inlet ends 30 which terminate within the inner portions of the spaces 21, respectively, just above their inner edges 13 and 14 of the baffles 11 and 12, and below the refrigerating mediums, as best shown in Figs. 1 and 2.

10 The refrigerating mediums 15 and 16 can be refrigerating coils, ice, dry ice, or any equivalent heat absorbing entity.

Particular attention is called to the fact that the bifurcated portions 28 and 29 of the pipe 27 15 terminate at location below the refrigerating mediums, and, as shown in Figs 1 and 2, in proximate relation to said refrigerating mediums, above the inner portions of the baffles 11 and 12, within the spaces 21. Naturally, the area with- 20 in the refrigerating case 10 at and directly surrounding the refrigerating mediums 15 and 16 is the coldest portion of said refrigerating case, so that the gaseous content of the refrigerating case which at any particular time surrounds the re- 25 frigerating mediums has greater density than the remainder of the gaseous content of said refrigerating case, and said gaseous content of greater density evidently will fall by gravity through the spaces 21, against the baffles 11 and 12, and 30 through the gap or space 23, as long as the tem- perature at the spaces 21 remains below the tem- perature of the storage space 22. And the denser gaseous content in so falling will create a siphon, 35 suction or vacuum action upon the inlet ends 30 of the bifurcated portions 28 and 29 of the pipe 27, to thus draw fresh atmospheric air into the spaces 21, said air passing with the falling denser gaseous content through the gap or passage 23 into the storage space 22. The incoming air is 40 condensed at the location of its meeting with the denser and colder gaseous content in the spaces 21, and thus the humidity of the air and the gaseous content is increased so that the whole 45 of the gaseous content of the refrigerating case is constantly kept sufficiently moist to in turn keep foods stored in the space 22 in proper condition precluding any shrinkage whatsoever of said foods. Also, upon the meeting of the incoming air with the colder gaseous content of the 50 case, and the passage by gravity of said air and relatively dense gaseous content through the gap or passage 23, the temperature of the content of the case falling through said gap or passage and downwardly through the central portion of the 55 storage space 22 has tendency to rise as said content moves farther from the gap or passage and closer to the bottom of the refrigerating case, as will be understood. The increase in temperature evidently decreases the density of the falling content, and eventually said downwardly moving 60 content becomes sufficiently light to start to rise, of course first spreading out over the lower portion of the refrigerating case, and finally the portion of the content which before passed down- 65 wardly through the gap or passage 23, finds its way out of the refrigerating case through the pipes 25, entering said pipes through the perforated branches 26 thereof. Some of the gaseous content repeats the cycle. Obviously, in a greater 70 or less period of time, the fresh air entering the refrigerating case through the pipe 27 and the bifurcated portions 28 and 29 thereof, will com- 75 pletely scavenge the case, any carbon dioxide freed from foods stored in the space 22 being forced to pass, sooner or later after becoming re-

moved from the foods, out of the refrigerating case by way of the outlet pipes 25. Or in other words, the arrangement as illustrated and fully described makes provision for the constant and continuous removal of carbon dioxide, as well as other deleterious gases, and deleterious odors, from the case, and the constant and continuous replacement within the case of fresh, pure air which will be sufficiently moist to insure the keeping of the foods in proper and desired condition.

In Figs. 4 to 8, numeral 31 denotes a refrigerating show case of oblong configuration, includ- 15 ing a counter portion having an oblique sight glass 32 and an oblique wall 33 opposite said sight glass. The wall 33 has sight glasses 33'. The show case 31 provides a refrigerating space 34 beneath said sight glass 32 and said oblique wall 33, and the lower portion of said space 34 has therein a conveniently supported food platform 20 35, said platform being in spaced relation to the bottom of the space 34, and desirably slanting from rear toward front of the show case. A refrigerating medium of any suitable nature is indicated 36, and is situated in the space 34 at location to the rear of and adjacent the platform 35, in spaced relation to said platform. An air inlet pipe 37 passes downwardly along the oblique wall 33, and leads from the atmosphere to the interior 25 of the show case, the lower portion of said pipe 37 including branches 38 which terminate at location between the refrigerating medium 36 and the platform 35, in proximate relation to said medium and platform as shown. Outlets from the show case, equivalent to the outlets 25 already described, consist of perforations 39 through the upper portion of the oblique wall 33.

The forward portion of the platform 35 is mounted in the refrigerating space 34 to provide a passage 40 for gaseous content of said refrigerating space, and a perforated wall 41 lies adjacent the branches 38 of the pipe 37, between the platform 35 and the refrigerating medium 36, to provide for passage of the gaseous content from the space above the platform 35 past the refrigerating 4 medium and to the space beneath said platform, the platform, in effect, and during the functioning of the refrigerator, serving as a baffle about which gaseous content of the refrigerating space 34 is constantly circulated, in the direction of the 5 arrows shown in Fig. 4.

Desirably, the branches 38 of the pipe 37 termi- 6 nate just below the refrigerating medium 36 and the platform or baffle 35. The manner in which the present refrigerator functions will be evident from the description made in connection with Figs. 1 to 3. The denser and consequently heavier, gaseous content surrounding the refrigerating medium 36 will fall to or toward the bottom of the refrigerating space 34, and in so falling will induce atmospheric air to enter said space 34 through the branches 38 of the air inlet pipe 37. The temperature of the falling content will rise, and the gases thus becoming less dense will find their way along the bottom of the platform or baffle 35 to the passage 40. Upon moving upwardly from said passage 40, some of the gaseous content will pass out of the outlets 39 and some of said content will pass through the perforated wall 41 back to the location of the refrigerating medium to repeat the cycle. In any event, and as will be obvious, all carbon dioxide, foul odors, etc., will eventually be passed out through the outlets 39, fresh air from the atmosphere con- 7 stantly and continuously replacing the removed

gaseous content in about the manner as hereinbefore set forth in connection with the embodiment of the invention illustrated in Figs. 1 to 3.

In Figs. 9 to 11, I have disclosed a further modified form of refrigerator made according to the invention. As there shown, the refrigerating case 42 is of oblong conformation, and includes an oblique sight glass 43 at the front thereof extending the greater portion of the height of the case. The lower portion 44 of the rearward wall of the case is vertically disposed, and the upper part of the portion 44 merges into an oblique, upper rearward wall 45 having sight glasses 46. The portion 44 includes doors 44'. The refrigerating space 47 of the show case 42 includes conveniently supported food platforms 48 which are in suitable spaced relation to each other.

A suitable refrigerating medium 49, extending along a considerable portion of the length of the show case, is horizontally situated just below the upper wall 50 of the case in spaced relation to the forward and rearward walls thereof. A baffle 51, desirably extending the full length of the show case, is disposed just beneath the refrigerating medium 49, and slants from front toward rear of the show case, the rearward edge portion of said baffle 51 desirably being in spaced relation to the rearward vertical wall 44 of the case.

The rearward portion of the baffle 51 merges into a downwardly disposed, convergent or funnel shaped receiver 52, which itself merges into a relatively large pipe 53, extending downwardly in the refrigerating space 47 at the rearward portion thereof, adjacent the food platforms 48, to position adjacent the bottom of said refrigerating space. As disclosed, the pipe 53 is vertically disposed, and is situated at the midlength of the refrigerating show case.

An air intake pipe 54 leads from the atmosphere to the interior of the show case. As disclosed, said pipe 54 passes through the oblique wall 45 of the show case, extends obliquely downwardly in the case between said oblique wall 45 and the baffle 51, and then vertically downwardly through the vertical pipe 53, in spaced relation to the wall of said pipe 53, the lower portion of the air intake pipe 54 obviously being of somewhat smaller diameter than the pipe 53. Outlets for carbon dioxide, odors, etc., in the upper portion of the wall supporting the sight glass 43, are represented 55.

The principle of operation of the refrigerating show case of Figs. 9 to 11 is the same as already set forth in connection with the disclosures of Figs. 1 to 8. The colder and denser, and consequently heavier, gaseous content of the show case in the vicinity of the refrigerating medium 49, obviously falls by gravity into the convergent or funnel shaped receiver 52, and thence through the relatively large pipe 53. The passage of said colder denser gaseous content out of the lower end of said pipe 53, induces a flow of fresh atmospheric air into the refrigerating space 47 through the air intake pipe 54, as will be evident. The gaseous content and air will, upon meeting with each other as the air enters the refrigerating space, become warmer, and hence less dense, and the less dense, lighter gaseous content will rise in the refrigerating space, to surround the platform 48. Eventually, the lighter gaseous content will pass upwardly through the space 56 be-

tween the baffle 51 and the forward wall of the case, and some of the gaseous content so passing will become removed from the refrigerator through the outlets 55, while the remainder of said gaseous content will pass the refrigerating medium and repeat the cycle as described. Upon the meeting of the incoming air and the denser gaseous content at the lower ends of the pipes 53 and 54, there is a general tendency toward condensation of the resultant gaseous content, making toward the keeping of the whole of the gaseous content in the refrigerator at the proper and desired degree of moisture. The relatively cold gaseous content passing through the pipe 53 about the pipe 54 cools the incoming air before it enters the refrigerating space.

It will be apparent that the action of purging the refrigerating space in the refrigerator of Figs. 9 to 11 is constant and continuous, about as already described, the fresh, pure air replacing the carbon dioxide, odors, etc., as these are removed from the refrigerator through outlets 55.

What is claimed is:

1. In a refrigerator, in combination, a casing forming a storage compartment, a refrigerating medium adjacent said storage compartment, a separator between said refrigerating medium and storage compartment and including a pipe leading from the location of said refrigerating medium into a lower portion of said storage compartment, an air inlet pipe leading from atmosphere and entering said storage compartment, said air inlet pipe being arranged within the pipe first mentioned in spaced relation thereto, said separator providing a passage for upward travel of a gas at a location in remote relation to said pipes, and an outlet for a gas leading from said refrigerator.

2. In a refrigerator, in combination, a casing forming a storage compartment, a refrigerating medium adjacent said storage compartment, a separator between said refrigerating medium and said storage compartment and including a funnel shaped member leading from the general location of said refrigerating medium into said storage compartment, an air inlet pipe leading from atmosphere to said storage compartment, said air inlet pipe being arranged within said funnel shaped member in spaced relation thereto, said separator providing a passage for upward travel of a gas at a location in remote relation to said funnel shaped member and said air inlet pipe, and an outlet for a gas leading from said refrigerator.

3. In a refrigerator, in combination, a casing forming a storage compartment, a refrigerating medium adjacent said storage compartment, a separator between said refrigerating medium and said storage compartment and including a funnel shaped member leading from said refrigerating medium to said storage compartment, an air inlet member leading from atmosphere and communicating with said storage compartment, said air inlet member being arranged within said funnel shaped member in spaced relation thereto, said separator providing a passage for upward travel of a gas at a location in remote relation to said funnel shaped member and said air inlet member, and an outlet for a gas leading from said refrigerator.
